UNITED STATES PATENT OFFICE

2,656,987

GRINDING MACHINE

Harold E. Drake, Fostoria, Ohio

Original application May 19, 1947, Serial No. 748,866. Divided and this application November 15, 1951, Serial No. 256,474

3 Claims. (Cl. 241—266)

1

This invention relates to a grinding machine. The invention is more particularly concerned with grinding plate supporting and controlling mechanism in grinding machines, and the present application is a division of my co-pending application, Serial No. 748,866, filed May 19, 1947, now abandoned.

A primary object of the invention is to provide relatively simple mechanism for maintaining opposed grinding plates in proper cooperative relation while same have reciprocatory movements imparted thereto in opposed directions.

A further object of the invention is to provide improved means for supporting grinding plates from vertically reciprocable arms.

A still further object of the invention is to provide novel grinding plates.

Other objects and advantages of the invention will become apparent in the course of the following detailed description, taken in connection with the accompanying drawing, wherein:

Figure 1 is a fragmental side elevational view of a grinding machine and disclosing the novel features of the present invention.

Fig. 2 is a side elevational view of a grinding machine, on substantially reduced scale, and showing the novel features of the present invention in operative association with a suitable mechanism for effecting vertical reciprocation of the rocker arms.

Fig. 3 is a top plan view of the grinding machine shown in Fig. 2 and to the same scale as Fig. 1.

Fig. 4 is a rear elevational view of one of the grinding plate-supporting channel members.

Fig. 5 is a front elevational view of one of the grinding plates.

Before proceeding with the detailed description, it is here pointed out that the novel features of the present invention are designated on the drawing by reference numerals, while the rocker arm reciprocating mechanism, which forms no part of the present invention, is designated by alphabetical letters, the said mechanism being shown solely for clarification of the operation of the rocker arms.

Referring now to the drawing, the present invention comprises two pairs of generally vertically disposed rocker arms 10 and 11 whose upper ends are pivotally connected to a pair of rocker bars 12, as is indicated at 13.

Disposed between the lower ends of each pair of rocker arms 10, 11 is a vertically elongated channel member. The opposite side flanges of

2

the channel members rest against the inner faces of the respective pairs of rocker arms 10, 11 and are secured thereto as by bolts 15.

The bases of the channel members oppose each other, and from Fig. 1 it will be seen that the rocker arms 10, 11 slightly converge downwardly from their pivotal connections 13, the upper portions of the bases of the channel members converge downwardly at a greater angle than the arms, and the lower portions of the bases converge downwardly at substantially the same angle as the rocker arms.

A grinding plate 16 is disposed on the front wall of the base of each channel member and adjacent the lower ends of the channel members.

Each grinding plate has a serrated face 17 and an upper angular face 17' which, with the aforementioned convergencies of the rocker arms and channel members, facilitate the feeding of materials to be ground between the serrated faces of the grinding plates.

Each grinding plate 16 is removably secured to a corresponding channel member by means of a pair of screw bolts 18 which extend through apertures 19 in brackets 20 at the rear of the channel member base, as well as the base, and which thread into tapped apertures 21 in the grinding plates.

The brackets 20 are provided with spaced apertured ears 22. Pivotally secured at one end thereof to ears 22 of one channel member, as by means of bolt 23, is a radius bar 24 whose opposite end is pivotally secured on a bolt 25 extending through ears 26 of brackets 27 which are secured as by bolts 28 to a suitable support 29.

Pivotally secured to the ears 22 of the opposed channel member as by means of a bolt 31 is one end of a radius rod 30 which is horizontally aligned with the radius bar 24. The rod adjacent its opposite end extends loosely through a block 32 pivotally secured to ears 33 of brackets 34 by means of studs 35. The brackets 34 are secured by bolts 36 to a suitable support 37.

The radius rod 30 is threaded at each side of the block 32, and an adjusting hand wheel 38 threadedly engages the rod beyond the block and is provided with a hub 39 engageable with the adjacent end of the block.

A nut 40 is threadedly engaged with the rod on the opposite side of the block, and a coil spring 41 is disposed between the nut and the adjacent end of the block in encircling relation to the rod.

The rocker arms 10, 11 may be vertically re-

ciprocated by various means, but a satisfactory mechanism for effecting such reciprocation may embody a rock shaft A rotatably supported adjacent its opposite ends in suitable fixed bearings B (only one of which is shown).

The pair of rocker bars 12 receive the shaft A and are secured thereto as by means of set screws C whereby the rocker bars are rockably movable with the shaft.

Interposed between the rocker bars and freely rotatable on the shaft A is a combined pulley and drive sprocket comprising a pulley D and a sprocket E. A shaft F extends through the rocker bars 12 adjacent each end thereof, and such shafts are secured to the bars by studs G.

A relatively large sprocket wheel H is rotatably supported on each shaft F in alignment with the smaller driving sprocket E and a sprocket chain I engages the sprockets E and H in the manner indicated in Fig. 2, whereby clockwise rotation of sprocket E imparts counterclockwise rotation to sprocket wheels H, as indicated by the arrows.

The small sprocket E is driven by a belt J from a suitable motor disposed above the machine.

Counterweights K are suitably attached to the sprocket wheels H, and the counterweight on one wheel is displaced 180° from that on the other wheel.

The momentum of the weights K is counterbalanced when disposed on opposite sides of the rock shaft A, but as the weights pass this position to that indicated in Fig. 2, wherein the left-hand weights are moving downwardly and the right-hand weights are moving upwardly, the rocker bars 14 and shaft A therewith will be rocked to the position indicated.

In this position, the left-hand grinding plate 16 has moved downwardly and the right-hand one upwardly. Upon further rotation of the sprocket wheels H and the weights K, those on the left will move upwardly, while those on the right will move downwardly, which will result in the rocker bars being rocked in an opposite direction.

The radius bar 24 and the radius rod 30 maintain the grinding plates 16 in proper operative relation, and one plate may be adjusted toward or from the other through operation of the hand wheel 38 to suit any particular grinding requirements.

Should metal or other hard objects enter between the grinding plates, the spring 41 will permit relative separation of the plates and thereby avoid damage thereto.

While I have disclosed my invention in accordance with a single specific embodiment thereof, such is to be considered as illustrative only, and not restrictive, the scope of the invention being defined in the following claims.

What I claim and desire to secure by U. S. Letters Patent is:

1. In a grinding machine, a pair of generally horizontal laterally spaced rocker bars supported substantially centrally of their ends on a shaft for rocking movement about the axis thereof, two opposed pairs of vertically reciprocable arms

having their upper ends pivotally connected to said rocker bars in equally spaced relation to the said axis of the shaft, a channel member disposed between the arms of each pair thereof adjacent their lower ends and having its side flanges secured thereto, the bases of the channel members opposing each other in slightly spaced relation, and a grinding plate secured to the base of each channel member in facing relation to each other.

2. The structure according to claim 1, together with a radius bar having one end thereof pivotally connected to one of said channel members and its opposite end pivotally connected to a fixed support, and a second radius bar having one end thereof pivotally connected to the other channel member and having an axially adjustable and pivotal connection with a fixed support.

3. The structure according to claim 1, together with a radius rod having one end thereof pivotally connected to one of said channel members, said rod slidably extending through a block pivotally connected to a fixed support, a spring adjustably supported on said rod at the side of said block adjacent said channel member, said rod being threaded at its opposite end, and an adjusting hand wheel threaded on said opposite end at the side of said block distant from said channel member and normally engaging the adjacent side of said block, and means horizontally positioning the other channel member.

HAROLD E. DRAKE.
